DISPLAY APPARATUS
 Michael H. Dirmeyer, Rydal, Pa.
 (3340 Rorer St., Philadelphia, Pa.)
 Filed Apr. 30, 1963, Ser. No. 277,423
 19 Claims. (Cl. 312—200)

This invention relates to display apparatus and in particular to compact, easily transportable and reusable display apparatus for trade shows and the like.

Trade shows, expositions, conventions and similar gatherings are by now a well-established and important feature of American business life. Many business concerns find it necessary, in order to be competitive, to display their wares at several shows each year and often choose such shows as the occasion for the first public announcement or showing of a new product. In order to save expense the same trade show exhibits are often used in a number of different shows. The cost of exhibiting such displays includes the labor, time and material costs incurred in assembling the display, disassembling it, re-crating it, shipping it, uncrating it and reassembling it at the next show.

It is therefore among the objects of the present invention to provide:

- (1) Display apparatus which is an attractive exhibit medium and a self-contained enclosure for storage or shipping purposes, and
- (2) A reusable, self-packaged and easily assembled and disassembled display apparatus.

Other objects of the invention will occur to those skilled in the art upon reading this application.

In accordance with my invention I provide a generally rectangular housing which is split into two parts and hinged along one narrow side thereof. On the side of the housing opposite the hinge, means are provided for securing both halves of the housing to one another when it is not being used for display or when it is in transit. When the apparatus is to be used for display, the securing means are released and both halves of the housing are opened until they are aligned with one another, the securing means can then be folded out of sight. Inside each half there is located an assembly which can be extended outwardly thereof to assist in maintaining the exhibit upright. This assembly may also include, for example, (1) space for advertising the name of the displaying company or its trademarks or other illustrative material, (2) means for illuminating the same, (3) a shelf on which items or descriptive literature may be placed, and (4) a planter. The inside panel of the housing itself is provided with a surface to which samples of the goods or flow charts, etc., may be connected, said samples, etc., being visible through space provided in the extensible assembly.

FIGURE 1 is a plan view of the novel display apparatus shown in its open or display position.

FIGURE 2 is a front elevation view of the apparatus shown in FIG. 1.

FIGURE 3 is a section view taken along the section lines 3—3 of FIG. 2 in the direction indicated and depicting the extensible assembly in three different positions.

FIGURE 4 is a section view taken along the section lines 4—4 of FIG. 2.

FIGURE 5 is a sectional view of the apparatus shown in FIG. 3 taken along the section lines 5—5 in the direction indicated.

FIGURE 6 is a view of the leg hinge portion of the extensible assembly as shown in FIG. 2 and taken along the section lines 6—6.

2

FIGURE 7 is an enlargement of the securing means shown within the broken-line rectangle 7 in FIG. 1.

FIGURE 8 is a sectional view of a modified form of the invention which includes a modified form of extensible assembly.

FIGURE 9 is an enlargement of part of the apparatus shown in FIG. 7.

FIGURE 10 is a sectional view of part of the apparatus shown in FIG. 7 showing the extensible assembly in its folded-in position for storage or transport.

Referring to FIGURES 1 and 2 in particular, there is shown indicated generally at the numeral 11 my novel apparatus which consists of two main parts or halves 11a and 11b connected together by a hinge 13 which may be a piano hinge, for example. Each of the halves 11a and 11b comprise a generally rectangular housing having a rectangular panel such as the panel 11c (FIG. 3) and includes respective forwardly-extensible assemblies indicated generally by the numerals 15 and 17. Flaps or end members 19 and 21 are affixed to the halves 11a and 11b by respective hinges 20 and 22. These end members, as will be explained in detail later, serve to secure the entire apparatus when the two halves are folded-over on one another as shown in phantom in the left side of FIG. 1.

Referring now additionally to FIGS. 3—7, it will be seen that the extensible assemblies 15 and 17 are, except for certain advertising lettering, substantially identical. In the interest of simplification therefore, the construction of assembly 17 only will be considered in detail. It comprises two rigid side supports 23 and 24 whose lower ends are pivotally attached to the housing by pivot pin such as the pin 26 shown in FIG. 3 and whose upper ends are connected for bracing and rigidity to a horizontal crossbeam 28f. Connected to the tops of the supports 23 and 24 and disposed between them is an illuminated display subassembly 28. This subassembly comprises two L-shaped bracket members 28a and 28b which are respectively connected by bolts or rivets to the supports 23 and 24. Channel members 28c and 28d are attached by bolts or screws, for example, to brackets 28a and 28b respectively. A panel 28e of frosted translucent plastic may be slid between the channel members 28c and 28d. This panel 28e may contain the name or part of the name of the company sponsoring the display, or depict the product, or bear the trademark, etc.

A fluorescent lighting fixture 28g which holds an elongated fluorescent light 28h is also connected to the rigid members 23 and 24. This light illuminates the plastic panel 28e from behind and also throws light out the top and bottom of the subassembly 28.

Near the middle of the members 23 and 24 are two brackets 29 and 31 having portions thereof pivotally connected to members 23 and 24 by pivot pins 29a and 31a respectively (FIG. 6). There are also connected to the brackets 29 and 31 folding rigid leg members indicated generally at the numerals 33 and 34. The upper ends of members 33 and 34 have two aligned transverse apertures therein (FIG. 6) through which respective pins or bolts 29b, 29c, and 31b, and 31c are passed. The lower ends of the members 33 and 34 are equipped with respective inner extensions 33a and 34a. The extensions 33a and 34a are made to slide up and down within legs 33 and 34 and are respectively equipped with transverse apertures such as aperture 33b (FIG. 4) into which respective pins are passed. One of these pins, numbered 33c, is illustrated in FIG. 4. It passes through one of two transverse apertures 33d and 33f in the rear of the leg 33. The pin 33c is connected by a chain 33g to the rear of leg 33. Before the legs 33 and 34 are folded back into the part 11b the extension 34a is pushed up until its

aperture 33b is aligned with aperture 33f and the pin 33c is then inserted therein.

Between the pivoting legs 33 and 34 a planter 36 for plants 35 may be located for purposes of rigidity and decoration. Alternatively, a cross-brace could be substituted for this purpose.

There is also connected between the legs 33 and 34 a pivoting shelf 40 which pivots about aligned pivot pins such as the pivot pin 41 in leg 33 shown in FIG. 5. The aligned pivot pin connected to member 34 is not shown in these drawings. The pivot pin 41 passes through a transverse aperture in the leg 33 and through another aperture aligned therewith in the shelf 40. To facilitate the pivoting action, the pin is passed through a bushing 42 and is secured at its inner end by a cotter pin 44 which passes through a transverse aperture toward the inner end of pin 41. Washers 45 and 46 are also provided for better pivoting action.

When the shelf 40 is in its horizontal position, its inner edge 40a rests freely upon a horizontal ledge 50 that is permanently affixed to the interior surface of the back wall of the panel 11c. On the shelf 40 may be placed, as shown in FIG. 2, descriptive literature such as the piles 55 shown, or samples or prototypes of the apparatus exhibited, for example.

In order to display the products being advertised, there is provided a mounting board 16 which is mounted to the interior surface of the back wall by nailing or otherwise affixing two horizontal wooden strips 61 and 62 (FIG. 3). The board 16 may be of the peg-board type which facilitates rearrangement of the products and easy affixation and demounting therefrom, or be of any other suitable material.

When it is desired to store or ship the display apparatus, the extensions of the legs 33 and 34, such as the pin 33c, are pushed up further into the legs after the pins have been refracted until the aperture in the extension is aligned with the upper aperture in the leg (see FIG. 4). Then the pin is reinserted in the upper aperture to lock the extension in this position. The legs 33 and 34 are then pulled forward until the end 40a of the shelf pivots downward and the entire assembly 17 is then pushed inside the portion 11b until it rests toward the rear thereof as shown in phantom in FIG. 3. When this has been done to both of the assemblies 15 and 17, the two halves 11a and 11b of the entire apparatus 11 are moved on their common hinge 13 toward one another until they are as shown in phantom in the left part of FIG. 1. The end members 19 and 21 are swung toward one another until they are as shown in the position depicted in FIG. 7 whereupon the bolt (or bolts) 57 is inserted in the aligned apertures as shown and a wing nut 58 or equivalent is screwed on.

As may be seen from FIGS. 8-10, there is another form which my invention may take. In this form, the planter 36 may be supplanted by simple cross beam 37 if desired and the upper end of the assembly 17' may be constrained to a maximum outward distance by using one or more chains 29 connected to the cross beam 28f and to the back wall 11c. However, the main difference is that there is a shelf 40' which is connected to the back wall 11c rather than to the legs 33 and 34 as in the former embodiment. The shelf 40' is hinged by a hinge 43 to a horizontal member 47 which is attached to 11c. The shelf is spaced somewhat from the member 47 by a space 48. Attached to shelf 40' on opposite sides are projections such as the projection 52 shown in FIGS. 8 and 9. There is cut into the lower edge of the projection 52 (and in the corresponding opposite projection) a notch 53 shaped to match the outline of a cross beam 54 upon which it rests when the assembly 17' is in its outward position. In order to ready the display apparatus for shipment or for storage, the front edge of the shelf 40' is lifted just sufficiently so that the notch 53 clears

the cross beam 54. Since the hinge 43 can swing upwardly and since there is a space 48 between the edge of the shelf 40' and the edge of the member 47, the shelf 40' can be moved sufficiently clockwise to enable the beam 54 to be dislodged from the notch 53. Then, the legs 33' and 34' are pushed inward, the lower extensions thereof having previously been pushed upward into the legs 33' and 34' and pinned in that position as shown in FIG. 10. As seen in that figure the shelf 40' hangs vertically from the hinge 43 and outwardly of the legs 33' and 34'.

General remarks

As shown in FIG. 2, the translucent panel 28e on the right half of the overall apparatus has its counterpart on the left side and the two are unconnected. This permits those panels to remain in the display subassemblies of each half of the casing when the apparatus is in its retracted position as shown in FIGS. 2 and 3. If desired, however, both of the panels could be supplanted by a single, slightly longer panel which could be slid out of the channel members 28c and 28d when the apparatus is to be retracted.

Furthermore, the invention may easily be used just with one of the halves, i.e., 11 rather than both, where a smaller or less expensive display is desired. In such a case, instead of having another half casing member such as the member 11a, the open side of the casing half 11b would be covered by two half doors or panels (not shown) hinged to the left and right edges thereof, their free edges meeting in the center when folded inward over the retracted portions.

Of course, other modifications of my invention which do not depart from the essence thereof will occur to those skilled in the art upon reading this specification. Consequently, I desire my invention to be limited only by the claims herein.

I claim:

1. Display apparatus comprising:

- (a) A selected number of generally hollow casing members,
- (b) A selected number of supporting members, one end of each member being movably mounted to an interior part of said casing,
- (c) A selected number of display subassemblies mounted to selected ones of said support members,
- (d) A selected number of legs each of which has one portion thereof coupled to a corresponding one of said supporting members and a free terminal portion thereof adapted to be placed on a supporting base, and
- (e) rigid means coupled to said casing for covering said casing.

2. The apparatus according to claim 1 wherein the free terminal portions of said legs are of adjustable length.

3. The apparatus according to claim 1 with the addition of shelf means coupled to said legs.

4. The apparatus according to claim 3 wherein said shelf means is also coupled to said casing means and is constructed to fold vertically.

5. Display apparatus comprising:

- (a) A generally hollow and shallow rectangular casing member having an open side therein, said member having an end wall for resting on a base whose depth is a small fraction of the height of said member,

(b) A pair of supporting members, the ends of the supporting members being pivotally mounted to interior points of said casing toward the lower end thereof,

(c) A display subassembly mounted to said supporting members toward the upper ends thereof,

(d) A pair of legs respectively having one end portion thereof coupled to one of said support members and a free end portion thereof which may be moved away

from said support member, said supporting members, display subassembly, and legs being arranged to be retracted into said casing or to be extended out therefrom to assist said end wall in maintaining said apparatus in an upright position on said base, and

(e) rigid means coupled to said casing for covering said open side when said support members, leg members and display subassembly are retracted therein.

6. The apparatus according to claim 5 wherein said display subassembly includes means for illuminating it.

7. The apparatus according to claim 5 wherein the free end portions of said legs are constructed to be of variable length and wherein said rigid means is an additional generally hollow and shallow rectangular member substantially identical to said casing member, said additional member having one vertical side wall thereof hinged to a vertical side wall of said casing member.

8. The apparatus according to claim 7 wherein said free end portions include inner axially movable extensions that may be pinned in desired positions and with the addition of two rigid flaps hinged to the outer side walls of said casing member and said additional rectangular member respectively, said flaps being equipped with mutually engaging fastening means.

9. The apparatus according to claim 5 wherein said one end portion of said legs are pivotally mounted to intermediate portions of said support members and wherein means visible between said supporting members are provided on the interior of said casing for exhibiting data or objects.

10. The apparatus according to claim 5 wherein shelf means coupled to said legs are additionally provided.

11. The apparatus according to claim 10 wherein said shelf means is also coupled to said casing means and is constructed to fold vertically.

12. The apparatus according to claim 10 wherein said shelf means is pivotally mounted between two of said supporting members and its rear edge portion is constructed to rest releasably on a part of said casing.

13. The apparatus according to claim 10 wherein said shelf means is hinged to a portion of said casing and is made to rest securely on a cross member connected between a pair of said supporting members, said shelf being constructed to hang vertically from said hinge when said supporting members and legs are in a retracted position.

14. Display apparatus comprising:

(a) at least one generally hollow and shallow casing member,

(b) at least one generally vertical supporting member, one end portion of each being mounted to a lower interior portion of said casing for angular movement outwardly thereof,

(c) at least one display subassembly mounted to and occupying a region near the upper end of said supporting member,

(d) at least one leg each having an upper portion thereof coupled to an intermediate portion of said supporting member, each leg having a lower portion thereof adapted to be placed on a supporting base, said lower portion having an adjustable length, said supporting member, display subassembly and leg being retracted into said casing member, and

5 15. The display apparatus according to claim 14 wherein said casing member has an inner, substantially vertical planar surface to which display material may be attached and wherein said display subassembly includes means for illuminating it and said display material on said vertical planar surface.

16. Display apparatus comprising:

(a) a generally rectangular and shallow casing member having one end wall intended to be placed on a supporting base, said end wall having a depth which is small relative to the height of said casing member, said casing member having an interior generally planar and vertical surface on which display material may be placed,

(b) two supporting members having their lower portions pivotally mounted to lower portions of the interior of said casing member,

(c) two legs of adjustable length, each having an upper portion coupled to intermediate portions of said supporting members and a lower axially movable portion whose lower ends are adapted to rest on said base when said supporting members and said legs are extended out of said casing member, said legs being laterally spaced to permit viewing of said generally vertical interior surface between them,

(d) a display subassembly mounted between the upper portions of said supporting members, said subassembly including means for illuminating it and display material on said vertical interior surface, and

(e) rigid means connected to said casing for providing a protective covering for said supporting members, legs, and display subassembly when they are retracted into said casing member.

17. Display apparatus according to claim 16 wherein said rigid means is a generally rectangular member substantially identical to said casing member, one vertical side wall of the former being hinged to one vertical side wall of the latter.

18. Display apparatus according to claim 17 wherein said rigid means also encloses two additional supporting members, two additional adjustable legs and an additional display subassembly mounted to said additional legs.

19. Display apparatus according to claim 17 with the addition of two rigid flaps respectively hinged to the respective outer vertical walls of said first-named casing member and said substantially identical rigid means, said flaps having mutually engaging securing means for fastening said flaps together and sealing said apparatus when said casing member and said substantially identical rigid means are folded into contact with one another.
